PILE REGULATOR

John D. Miner, Jr., and Harry D. Else, Lima, Ohio,
assignors to Westinghouse Electric Corporation,
East Pittsburgh, Pa., a corporation of Pennsylvania

Application August 17, 1948, Serial No. 44,597

6 Claims. (Cl. 201—51)

1

This invention relates to pile regulators and, in particular, to pile regulators of the lightweight aviation type.

Lightweight carbon pile regulators have recently been developed for use in airplanes. Generally, such regulators comprise a stack of discs of resistance material, the pressure of which is controlled by an electromagnet having a special spring-mounted armature assembly, cooling fins being provided about the stack for dissipating heat therefrom, the entire structure being held in assembled relation by tie bolts extending the length of the assembly. In the regulators produced heretofore, considerable trouble has been encountered by reason of the different expansion characteristics of the components of the regulator, and attempts have been made with different degrees of success to compensate for the different expansion characteristics while retaining a strong lightweight structure which will have a stable operation.

An object of this invention is to provide a lightweight compact pile regulator provided with cooling fins in which the electromagnet for controlling the pressure applied to the pile is supported in operative relation at one end of the pile independently of the overall fin structure.

Another object of this invention is the provision in a pile regulator having a metallic housing for supporting the pile and cooling fins for dissipating heat therefrom, for supporting the electromagnet assembly directly from the metallic housing at one end only thereof whereby compensation for thermal expansion is unnecessary.

A further object of this invention is to provide strong supporting surfaces in designated zones in relation to the cooling fin structure of a pile regulator whereby the regulator may be supported in assembled relation.

Other objects of this invention will become apparent from the following description when taken in conjunction with the accompanying drawing, in which:

Figure 1 is a view in side elevation and partly in section of a pile regulator embodying the teachings of this invention;

Fig. 2 is a front end view of the regulator of Fig. 1;

Fig. 3 is a partial rear end view of the regulator of Fig. 1; and

Figs. 4 and 5 are partial views, partly in section, illustrating different embodiments of the stack housing and fin structure utilized in the regulator.

Referring to the drawing, and in particular to

Figure 1 thereof, there is illustrated a pile regulator 10 formed of a stack 12 of discs 14 of resistance material disposed between a relatively fixed pressure plate 16 and a movable pressure plate 18 with an electromagnet assembly 20 disposed in aligned relation with the stack 12 for controlling the pressure applied thereto.

The electromagnet assembly 20 illustrated is enclosed in a sectionalized housing, one section 22 of which comprises the magnetic iron structure for the electromagnet and is formed of a base plate 24, side plate 26 and end plate 28, the latter functioning as pole pieces for the electromagnet, and a centrally disposed core member 30. The core member 30 is adjustably mounted in the base plate 24, the base plate 24 also being provided with suitable lugs 32, as better illustrated in Fig. 2 to aid in assembling the electromagnet assembly, as will be explained more fully hereinafter. As illustrated, an energizing coil winding 34 is disposed within the section 22 of the housing about the core piece 30, being suitably insulated from the magnetic structure of the electromagnet.

An armature assembly 36 is disposed between the pole pieces 28 and the movable pressure plate 18 for controlling the pressure applied to the stack 12 in accordance with the energization of the electromagnet. As illustrated, an abutment member 38 is disposed to be seated upon the face of the electromagnet 20, the abutment 38 having a sloped surface 40 provided thereon for cooperating with a spring member 42 which is carried by the armature assembly 36 for applying pressure to the stack 12. In the embodiment illustrated, the armature assembly is formed of an armature member 44 centrally disposed with respect to the abutment member 38, the spring member 42 being clamped between two aligned washer members 46 and 48 to the armature member 44 by means of screws 50. As disclosed in Patent No. 2,408,188, issued September 24, 1946 to B. O. Austin, a damper member or diaphragm 52 is secured between the washer member 46 and the armature member 44 so that it extends beyond the edges of the armature member 44 and is held in position between the abutment 38 and the pole piece 28. A sleeve 54 of insulating material is centrally disposed with respect to the washer members 46 and 48 and is held in position by means of an overlapping ring washer 58 the inner edge of which seats against a shoulder provided on the sleeve 54. The screws 50 effectively hold the components of the armature assembly together as an integral component.

As illustrated, the stack 12 is disposed within a tubular housing member 60 formed of steel, Invar, brass or any other suitable metal, the outer surface of which is roughened as by knurling or otherwise. In a preferred embodiment, as illustrated in Fig. 1, the outer surface of the tubular housing 60 is provided with longitudinal flutes 62 which extend lengthwise of the housing 60 in spaced relation about the housing. In another embodiment illustrated in Fig. 4, the outer surface of the housing 60 may be provided with circumferential ribs 64 disposed in spaced relation lengthwise of the housing, or as illustrated in Fig. 5, the outer surface may be provided with circumferential grooves 66 disposed in spaced relation lengthwise of the housing. The housing 60 may be of any suitable metal, although it is preferred to utilize a metal having a coefficient of linear expansion over the operating range of the regulator comparable to the coefficient of expansion of the resistance material forming the stack 12. However, excellent results have been accomplished by employing steel or Invar, a 36% nickel-iron alloy which has a substantially zero coefficient of thermal expansion as the composition of the tubular housing 60.

In order to provide for dissipating heat generated in the stack 12 during the operation of the regulator, cooling fins 68 of aluminum or the like are disposed in spaced relation one from the other lengthwise of the housing 60, the cooling fins 68 being substantially independent one from the other. As illustrated, the cooling fins 68 are relatively thin and have very thin base portions adjacent the housing 60 so that even though the cooling fins 68 have a different coefficient of expansion from that of the housing 60, very little stress is encountered at the junction between the cooling fins and the housing at the narrow portion of the cooling fin 68, and the bond therebetween is maintained under operating conditions. Preferably, the fins 68 are cast in position with respect to the housing 60, it being found that the roughened surface of the housing 60 interlocks with the bases of the cast cooling fins 68 to provide strong joints therebetween whereby the cooling fins 68 are maintained in the spaced relation on the housing 60.

In order to provide for a simplified assembly of the electromagnet and to provide a suitable housing for the armature assembly 36, the section 70 of the sectionalized housing for the electromagnet 20 is preferably formed of the same metal as that of the cooling fins 68, being formed as a unitary structure with the terminal fin 68' at the one end of the stack 12 adjacent the movable pressure plate 16. Thus, the section 70 is formed of aluminum, being of a cup shape for encompassing the armature assembly 36 and is formed simultaneously with the terminal fin 68', a common hub 72 being formed integrally therewith. The hub 72 may be quite thin but is securely interlocked with the roughened surface of the housing 60 whereby the unitary structure comprising the section 70 of the sectionalized housing is securely mounted on the end of the housing 60 and the joint or supporting surface thus formed has sufficient strength to carry the weight of the electromagnet assembly 20.

In order to secure the sections 22 and 70 of the sectionalized housing for maintaining the electromagnet assembly 20 in operation position with the armature assembly 36 disposed to control the pressure applied to the stack 12, a plurality of bolts 14 are disposed to connect the

5 lugs 32 of the base plate 24 to the side wall members of the section 70 of the housing whereby the electromagnet assembly 20 is maintained in operative position independently of the cooling fin structure, being entirely supported at one end only of the housing 60.

10 At the opposite end of the housing 60, that is adjacent the fixed pressure plate 16, a plate 76 is secured to the terminal fin 68'' by means of spaced screws 78, as better illustrated in Fig. 3, a sheet of insulating material 80 such as mica being disposed between the plate 76 and the end of the housing 60 and the fin 68''. As illustrated in Figs. 1 and 3, a plug 82 is disposed in threaded engagement with the plate 76 for receiving the end of the pressure plate 16, the plug 82 being adjustable for initial adjustment of pressure on the stack 12. In order to maintain the plug 82 in a fixed position once the initial adjustment has been made, the plate 76 is provided with a split ring assembly 84 which is disposed to be tightened about the plug 82 by means of the screw 86. A terminal 88 is carried by the plate 76 for making the electrical connections thereto.

15 In order to provide adequate support for the end plate 76 and plug 82 carried thereby, the terminal fin 68'' adjacent that end of the stack is preferably cast as an integral unit with the adjacent cooling fin 68 with a common hub 90 therebetween. The hub 90 is interlocked with the roughened surface of the housing 60 and functions in the same manner as the hub 72 referred to hereinbefore for providing adequate support for the assembly attached thereto.

20 In order to provide for supporting the assembled electromagnet on a base member 92, three of the fins 68 disposed intermediate of the fin structure are formed with common hubs 94 therebetween. The central fin 68'', thus formed can be attached to a flange 91 of the base member 92 as by means of the screw 96, as illustrated, the fin being provided with adequate strength by reason of the interlocking support of the hub members 94 with the housing 60. Another flange 93 of the base member 92 is also secured to the end of section 70 of the sectionalized housing by means of screws 98, as illustrated in Fig. 2, whereby the pile regulator is assembled on the base member with the electromagnet 20 and the stack 12 assembled in operative relation therein, the entire assembled structure being lightweight and compact. As in usual practice, the base member 92 is illustrated as also carrying a variable resistor 100 and a fixed resistor 102 and other connections not shown, terminal plugs 104 being carried on one side of the base member 92 for facilitating plug-in mounting of the regulating assembly.

25 In operation, the regulator of this invention functions in the normal manner, in that the spring 42 tends to compress the stack 12 of discs 14, whereas the armature member 44 works against the influence of the electromagnet 20 to relieve the pressure on the stack 12. In practice, as the stack 12 becomes heated and tends to expand, it is found that any accompanying expansion of the tubular housing member 60 will not interfere with the functioning of the cooling fins 68 for the bond between the cooling fins and the roughened surface of the housing 60 is over such a narrow area that the bond will not be ruptured. This is also true of the hub sections 72, 90 and 94 illustrated, it being found that the interlocking support be-

tween the hubs 72, 90 and 94 and the roughened surface 62 is also of such a small portion of the overall structure of the housing 60 that the bond therebetween is unaffected by any difference between the expansion characteristics of the cooling fin metal and that of the tubular housing. The length of the hubs 72, 90 and 94, however, is sufficient to prevent working of the joint between the housing and the hub structures under stresses encountered in operation.

In addition, since the sectionalized housing for the electromagnet assembly is supported at one end only of the tubular housing 60, and since the sections of the sectionalized housing for the electromagnet are maintained in assembled relation by means associated only with the sections of the housing independent of the cooling fins, it is found that the support of the electromagnet housing is free of any difficulties caused by a difference of expansion of the components of the housing for the stack and the fins. The regulator is very efficient in operation and can be readily reproduced by anyone skilled in the art.

We claim as our invention:

1. A pile resistor comprising, in combination, a stack of discs of resistance material, relatively fixed pressure plate at one end of the stack, a movable pressure plate at the other end of the stack, an electromagnet comprising an energizing winding and an armature assembly disposed to be operated to actuate the movable pressure plate to control the pressure applied to the stack, a sectionalized housing for the electromagnet, a tubular housing member for the stack, the tubular housing member being of metal having a predetermined coefficient of expansion, a plurality of cooling fins of metal disposed about the tubular housing member in spaced relation lengthwise thereof, the cooling fins having a coefficient of expansion different from that of the tubular housing member, one section of the electromagnet housing being disposed to encompass the armature assembly, said one section being of the same metal as the cooling fins and being unitary with the terminal fin adjacent one end of the tubular housing member, said one section and the terminal fin having a common hub formed integrally therewith in contact engagement with the tubular housing member to provide a strong support for the sectionalized housing whereby the assembled sectionalized housing is maintained in assembled relation with respect to the tubular housing member with the electromagnet and stack assembled therein.

2. In a pile regulator having a stack of discs of resistance material assembled in a tubular metallic member and having an electromagnet assembly for controlling the pressure applied to the stack, the combination comprising, a plurality of metallic cooling fins disposed about and in direct contact with the tubular member independently of one another and in spaced relation lengthwise thereof, the tubular member having an irregular outer surface for cooperating with the fins to maintain them in their spaced assembled relation thereon, a sectionalized housing for the electromagnet assembly, securing means disposed in cooperation only with the sections of the sectionalized housing for securing and holding the sections of the housing assembled with the electromagnet assembly therein, one section of the housing being of the same metal as the cooling fins and being unitary with the terminal fin adjacent one end of the tubular member, said section of the housing and terminal fin having a

common hub formed integrally therewith in contact engagement with the tubular member to provide the sole support for the housing whereby the assembled sectionalized housing is maintained in assembled relation with respect to the tubular member.

3. In a pile regulator having a stack of discs of resistance material assembled in a tubular metallic member and having an electromagnet assembly for controlling the pressure applied to the stack, the combination comprising, a plurality of metallic cooling fins disposed about the tubular member independently of one another and in spaced relation lengthwise thereof, a plurality of ribs disposed in spaced relation on the outer surface of the tubular member for cooperating with the fins to maintain them in their spaced assembled relation thereon, a sectionalized housing for the electromagnet assembly, securing means disposed in cooperation only with the sections of the sectionalized housing for securing and holding the sections of the housing assembled with the electromagnet assembly therein, one section of the housing being of the same metal as the cooling fins and being unitary with the terminal fin adjacent one end of the tubular member, said section of the housing and terminal fin having a common hub formed integrally therewith in contact engagement with the tubular member to provide the sole support for the housing whereby the assembled sectionalized housing is maintained in assembled relation with respect to the tubular member.

4. A pile resistor comprising, in combination, a stack of discs of resistance material relatively fixed pressure plate at one end of the stack, a movable pressure plate at the other end of the stack, an electromagnet comprising an energizing winding and an armature assembly disposed to be operated to actuate the movable pressure plate to control the pressure applied to the stack, a sectionalized housing for the electromagnet, a tubular housing member for the stack, the tubular housing member being of metal having a predetermined coefficient of expansion, a plurality of cooling fins of metal disposed about the tubular housing member independently of one another and in spaced relation lengthwise thereof, the cooling fins having a coefficient of expansion different from that of the tubular housing member, one section of the electromagnet housing being disposed to encompass the armature assembly, said one section being of the same metal as the cooling fins and being unitary with the terminal fin adjacent one end of the tubular housing member, said one section and the terminal fin having a common hub formed integrally therewith in contact engagement with the tubular housing member to provide a strong support for the sectionalized housing whereby the assembled sectionalized housing is maintained in assembled relation with respect to the tubular housing member with the electromagnet and stack assembled therein.

5. A pile resistor comprising, in combination, a stack of discs of resistance material, a relatively fixed pressure plate at one end of the stack, a movable pressure plate at the other end of the stack, an electromagnet comprising an energizing winding and an armature assembly disposed to be operated to actuate the movable pressure plate to control the pressure applied to the stack, a sectionalized housing for the electromagnet, one section of the electromagnet housing being disposed to encompass the armature assembly and

the movable pressure plate, means associated only with the sectionalized housing for holding the sections assembled with the electromagnet therein, a tubular housing member for the stack, the tubular housing member being of metal having a predetermined coefficient of expansion, a plurality of cooling fins of metal disposed about the tubular housing member in spaced relation lengthwise thereof, the cooling fins having a coefficient of expansion different from that of the tubular housing member, said one section of the electromagnet housing being of the same metal as the cooling fins and being unitary with the terminal fin adjacent one end of the tubular housing member, said one section and the terminal fin having a common hub formed integrally therewith in contact engagement with the tubular housing member to provide a strong support for the electromagnet housing whereby the assembled sectionalized housing is maintained in assembled relation with respect to the tubular housing member with the electromagnet and stack assembled in operative relation therein.

6. A pile resistor comprising, in combination, a stack of discs of resistance material, a relatively fixed pressure plate at one end of the stack, a movable pressure plate at the other end of the stack, an electromagnet comprising an energizing winding and an armature assembly disposed to be operated to actuate the movable pressure plate to control the pressure applied to the stack, a sectionalized housing for the electromagnet, one section of the electromagnet housing being disposed to encompass the armature assembly and the movable pressure plate, means associated only with the sectionalized housing for holding the sections assembled with the electromagnet therein, a tubular housing member of steel for the stack, the tubular housing member having a roughened outer surface, a plurality of cooling fins of cast aluminum disposed about the tubular

housing member independently of one another and in spaced relation lengthwise thereof, the aluminum fins being interlocked with the roughened surface of the tubular housing member to retain them in position thereon, said one section of the electromagnet housing also being of aluminum and being formed as an integral unitary part with a terminal fin adjacent one end of the tubular housing member, said one section and the terminal fin having a common hub formed integrally therewith in interlocking engagement with the roughened surface of the tubular housing member to provide a strong support for the electromagnet housing whereby the assembled sectionalized housing is maintained in assembled relation with respect to the tubular housing member with the electromagnet and stack assembled in operative relation therein.
